GRINDING APPARATUS

Walter J. Greenleaf, Meadville, Pa., assignor to
McCrossy Tool Corporation, Meadville, Pa.

Application July 15, 1941, Serial No. 402,447

12 Claims. (Cl. 51—34)

This invention relates to grinding apparatus, and, particularly, is concerned with apparatus of this type adapted to grind, surface, shoulder, or otherwise treat, shape or dress a machine tool or the like.

It is the general object of my invention to provide relatively simple, inexpensive, readily operated, apparatus of relatively light weight and small size for grinding machine tools and the like and which can be very quickly adjusted and operated to perform substantially any desired operation of this character.

Another object of my invention is the provision of tool grinding apparatus and the like and wherein costly machine V-slides are eliminated by the use of a completely practical and much less expensive type of slide and which are positioned at points in the apparatus so that substantially no dust from the grinding operation can work into the slide.

Another object of my invention is the provision of improved apparatus of the character indicated and wherein ball and socket means of an almost instantaneously adjustable nature are provided for supporting the tool at exactly the angle desired during the grinding operation.

Another object of my invention is the provision of improved motor mounting means.

Another object of my invention is to provide apparatus for grinding tools and the like and wherein the vise for supporting the tool is readily adjusted either longitudinally or laterally of the apparatus and can be quickly clamped at any desired tilted angle.

Another object of my invention is the provision of grinding apparatus for forming chip breaking shoulders on a machine tool, or for performing other similar operations, and wherein the tool is readily clamped at the desired angle and the grinding wheel is moved over the top of the tool and with all parts of the apparatus supporting the grinding wheel in its sliding movement being so protected, covered, and positioned, that it is substantially impossible for any deteriorating amount of grinding dust to work into the sliding support for the grinding wheel and thereby lessen its operating life.

For a better understanding of my invention reference should be had to the accompanying drawings wherein Fig. 1 is a side elevation partly in section of one embodiment of my apparatus; Fig. 2 is a plan view of the apparatus shown in Fig. 1 but with the greater part of the tank for supplying cutting fluid to the grinding wheel being broken away to better illustrate the details

of the apparatus structure; Fig. 3 is a cross-sectional view taken on line III—III of Fig. 2; and Fig. 4 is a cross-sectional view taken on line IV—IV of Fig. 2.

In the drawings, the numeral 10 indicates generally a base member usually formed with a flat side 12 and a curved side 14. Formed integral with the base member 10 is a flat, slightly up-raised table 16 having a ground or machined upper surface and provided with a longitudinally extending slot 18. A vise, indicated as a whole by the numeral 20, has a bottom portion 22 which is mounted in a longitudinally adjustable position on top of the table 16. This is ordinarily achieved by providing the support 22 with laterally extending ear members 24 which receive bolts 26 that extend into the slot 18 in the table 16. Thus, the support 22 for the vise 20 can be readily clamped in any desired adjusted position upon the base 10 of the apparatus.

The vise 20 includes a turret 28 which is carried in a laterally adjustable position on the support 22. To this end, the turret 28 has secured thereto a bolt 30 which extends horizontally from the turret 28 to and through an upstanding lug 32 formed integrally with the support 22. Nuts 34 screwed on to the bolt 30 on opposite sides of the lug 32 provide means for adjusting the turret 28 laterally of the base 10 on the support 22. In order to clamp the turret 28 on the support 22 in the adjusted position, I provide clamping means which may take the form of a cap screw 36 which extends upwardly through a slot 38 running along the center line of the support 22. The cap screw 36 extends up through the center of the turret 28, and threaded on the end of the cap screw 36 is a clamping nut 40 having an operating arm 42 secured thereto. The operating arm 42 extends out through the side of the turret 28 which is suitably slotted horizontally to permit the arcuate movement of the operating arm 42. The clearance between the several parts of the structure just described, and the thread pitch of the cap screw 36 and clamping nut 40 is such that a relatively small arcuate movement of the operating arm 42 will either clamp or release the turret 28 on the support 22. Before leaving the description of the mounting of the turret 28 on the support 22, it should be noted that in certain installations I may dispense with the use of the bolt 30, lug 32, and nuts 34. When this mechanism is not employed the clamping action provided by the cap screw 36 and clamping nut is all that is required and the turret 28 is moved by hand laterally of the base 10 and can also be

moved angularly about the cap screw 36 as a pivot. However, I usually employ the bolt 30 and associate mechanism in the preferred embodiment of my invention although I am not to be limited to their use.

The top of the turret 28 is formed as a socket and tiltably receives a ball member 46 which is adapted to be clamped in the turret by mechanism which includes a stud bolt 48 extending axially through the ball member 46 and the turret 28. The lower end of the stud bolt 48 is threaded and receives a clamping nut 50 having an operating arm 52 secured thereto and extending out laterally of the turret through a suitable slot cut in the side wall of the turret. The upper end of the stud bolt 48 carries a half ball 54 which is adjustably mounted on the stud bolt by suitable complementary threads. The half ball is provided with suitable recesses 56 for a spanner wrench whereby the position of the half ball on the stud bolt can be adjusted. The end of the stud bolt 48 adjacent the half ball 54 is suitably drilled and tapped and receives a slightly tapered locking plug 58 whereby once the half ball 54 is adjusted to the proper position on the end of the stud bolt 48 the locking plug 58 is turned down into the end of the stud bolt to lock the half ball in the desired position on the end of the stud bolt. By these means any wear on the ball member 46, half ball 54 or other parts of the assembly may be readily compensated for so that the desired clamping action of the ball member 46 to the turret 28 and in any position is achieved by moving the operating arm 52 carried by the clamping nut 50. The half ball 54 is received within a suitable hemispherical recess in the center of the ball member 46.

The ball member 46 carries the vise proper which may obviously take a plurality of forms. The purpose of the vise proper, which has been indicated by the numeral 62, is to support any desired article to be ground. When working on machine tools, bits, and other similar articles, for which the present invention is particularly adapted, I ordinarily provide a vise proper which is in the form of a U-shaped channel or bracket having its base portion secured by any suitable means to any desired tapped hole 64, T-slots or other means formed in the upper surface of the ball member 46. The sides of the channel shaped vise proper carry one or more clamping screws 66 which can be readily moved inwardly to grip a tool or other member to be ground firmly between the sides of the channel. To simplify the illustration of my improved apparatus, and to render the showing thereof clearer, I have not shown in Fig. 2 of the drawings the vise proper 62 illustrated in Fig. 1. However, it will be understood that in the ordinary use of my apparatus some suitable means, such as the vise proper 62, are ordinarily incorporated in the apparatus on top of the ball member 46.

In combination with the vise for holding the tool or other member to be ground I provided a carriage, indicated as a whole by the numeral 70, which is mounted for sliding movement parallel to the base 10 and in a position offset laterally from the vise assembly 20. Specifically, the carriage 70, having a shape in plan as shown in Fig. 2 of the drawings and a downwardly extending flange 72 around substantially the entire periphery of the carriage, is given a three point sliding support on the base member 10. This is achieved by mounting brackets 76 and 78 on opposite ends of the base 10 with the brackets serving to sup-

port the shaft 80 between them with the shaft 80 being parallel to the base 10 but spaced at a considerable vertical distance thereabove. As best seen in Fig. 3, the carriage 70 has secured to its under side a block 82 which mounts rotatably a pair of rollers 84 at right angles to each other and so they will roll upon the upper surface of the shaft 80. Cooperating with the rollers 84 is a roller 86 rotatably carried by a suitable bracket 88 secured to the carriage 70. One unit or assembly of rollers 84 and 86 is mounted near one end of the carriage 70, and a second unit or assembly of rollers 84 and 86 is mounted near the other end of the carriage 70 so that the carriage is given rolling support on the shaft 80. Before leaving the unit or assembly of rollers 84 and 86 shown in Fig. 3 it should be noted that the roller 86 is not positioned directly opposite the rollers 84, but instead, is mounted in a plane having substantially an angle of about 20 degrees with the vertical. This construction has been found to be superior from the standpoint of wear and wear takeup of the parts of the roller assembly. Obviously, the wear on the rollers 84, 86 and shaft 80 is relatively small, particularly inasmuch as they are substantially covered and protected by the flange 72 on the carriage 70. The roller 86, of course, keeps the carriage 70 from jumping off of the shaft 80.

The carriage 70 is also given sliding support on the base 10 at a third point. Having reference to Fig. 4, the numeral 90 indicates a bracket secured to the base 10. The bracket 90 carries a cap screw 92 which extends through a longitudinally extending slot 94 formed in the carriage 70. Sufficient clearance is allowed between the head of the cap screw 92 and the carriage 70 so that a free sliding movement of the carriage 70 with respect to the cap screw 92 is obtained. It should be noted in conjunction with the structure shown in Fig. 4 that substantially all of the weight carried by the carriage 70, and hereinafter described, is concentrated above the shaft 80. Thus, the weight of the carriage 70 on the bracket 90 is relatively small and friction is at a minimum although no rolling support for the carriage is provided. Although I may, of course, employ some suitable rolling support for the carriage 70 on the bracket 90 I have found that this is unnecessary in most instances and adds to the expense of the structure where only a steady action is required by the bracket 90.

The extent of longitudinal movement of the carriage 70 on the base 10 can be readily controlled, adjusted, or limited. For this purpose I provide an arm 96 which is secured to one end of the carriage. The arm 96 carries a rod 98 which extends slidably through a support 100 fastened to the bracket 78. Collars 102 adjustably positioned on the rod 98 control the extent of longitudinal movement of the carriage 70 by striking the support 100 carried on the bracket 78.

I have provided relatively simple but positive means for moving the carriage 70 longitudinally of the base 10. Particularly, I form a bracket 106 integral with the bracket 78 and to the bracket 106 pivotally secure a link 108. The other end of the link 108 is pivotally secured to an arm 110 having an operating handle 112 which extends out to the front of the machine and in a position handy to be reached and operated by the user of the apparatus. The arm 110 is pivotally secured at 114 to a suitable lug 116 formed integral with the end of the carriage 70. By

moving the handle 112 back and forth in a horizontal plane the carriage 10 is given a desired horizontal movement.

A motor platform 120 is pivotally mounted on the carriage 10 as by means of pointed pivot screws 122 extending through suitably tapped openings formed in upstanding lugs 124 carried by or formed integrally with the carriage 10. The pointed pivot screws 122 extend into suitable conical recesses provided in the sides of an extension 126 formed integral with the motor platform 120. Lock nuts 128 serve to secure the pointed pivot screws 122 in their adjusted position. The unpivoted end of the motor platform 120 is adjustable vertically in any suitable manner. Conveniently, I provide a vertically extending post 130 which is secured to or formed integrally with the top of the carriage 10 and which supports a bolt 132 which extends up through a suitable recess in the motor platform 120 and carries a hand-wheel nut 134. A coiled compression spring 136 positioned between the carriage 10 and the motor platform 120 serves to hold the motor platform up against the hand-wheel nut 134. Suitable micrometer means 138 may be associated with the hand-wheel nut 134 so that the exact vertical position of the unpivoted end of the motor platform 120 is indicated at all times.

Mounted upon the motor bracket 120 is an electric motor 140 which has a drive shaft 142 on which is mounted a grinding wheel 144. Ordinarily, I provide some suitable cutting or cooling medium which is adapted to be continuously discharged or dropped upon the grinding wheel 144. This is conveniently accomplished by the provision of a storage tank 146 having downwardly extending legs portions 148 which straddle the motor 140 and which are secured to the motor bracket 120 by a suitable means, such as screws 150. The storage tank 146 has an outlet tube 152 extending therefrom and terminating at a point immediately above the grinding wheel 144, as best seen in Fig. 1. A valve 154 controls the flow of fluid from the tank 146 through the conduit 152. Adjusting the valve 154 gives exactly the desired type of flow of the cutting fluid or cooling medium from the tank 146 for any given type of grinding operation. The storage tank 146 has not been illustrated completely in Fig. 2 of the drawings, but has been broken away to better illustrate the assembly of the apparatus.

It is believed that the operation of my improved apparatus will be apparent from the foregoing detailed description. However, briefly reviewing the operation of my improved apparatus, a tool or other member to be ground is mounted in the vise proper 62 being clamped in position by means of the screws 66. The ball member 46 is then tilted or adjusted to the desired position and the operating arm 52 is tightened to clamp the ball member 46 in the desired position. The turret 28 of the vise assembly 20 is then moved laterally of the base member 40 by adjusting the nuts 34 and is clamped tightly in position by the operating arm 42. The position of the vise assembly 20 on the base 40 is controlled by the bolts 26 which may be loosened and the whole vise assembly moved longitudinally of the base member to the desired position after which the bolts 26 are tightened. It will be recognized that the exact sequence of adjusting operations as just described may be varied considerably, but that in any event after all of the adjustments are made the tool or other articles to be ground

will be held in the desired relation and at the proper angle for the grinding operation.

The vertical position of the grinding wheel 144 with respect to the tool or other article to be ground is now adjusted by means of the hand-wheel nut 134, and the motor 140 is started by closing suitable switch means (not shown). Thereafter, the handle 112 is grasped by the operator of the apparatus and is swung in a horizontal direction to move the carriage 10 in a horizontal plane to thereby cause the grinding wheel 144 to pass over the tool or other article to be ground. This movement results in a grinding cut of desired extent upon the surface of the tool or other articles being ground. Adjusting the hand-wheel nut 134 in conjunction with movement back and forth of the handle 112 results in a grinding operation of the desired extent on the tool or other article being ground.

From the foregoing it will be recognized that the objects of my invention have been achieved by a relatively simple, easily operated, inexpensive, fool-proof, long wearing, apparatus of relatively small size and weight and capable of performing substantially any desired type of grinding operation upon tools for automatic machines and the like. The use of expensive structural machine parts has been avoided and maintenance expense and care is at a minimum. Provision has been made for ready takeup of any worn parts in the assembly, and the arrangement of parts is such that grinding dust cannot fall upon any parts of the apparatus which are subject to considerable wear.

Although I have particularly described my invention as embodying a horizontal base, horizontal carriage movement, and the like, it should be understood that any of the features of the invention may be embodied in apparatus having other than a horizontal base and horizontal carriage movement. Therefore, and because of similar alterations which may be made in the apparatus without departing from the spirit thereof, it should be particularly understood that I am not to be limited by or to the particular embodiment of my invention which I have illustrated in detail in accordance with the patent statutes. Instead, the scope of my invention is defined by the appended claims.

50. I claim:

1. Apparatus for grinding chip breaking shoulders and the like comprising a tool vise, a ball and socket support for the vise, means for clamping the vise in any desired tilted position, a base, means mounting the vise in a longitudinally adjustable position on the base, means for adjusting the lateral position of the vise on the base, a carriage, means slidably mounting the carriage for movement parallel to the base but spaced laterally from the vise, means for adjustably limiting the movement of the carriage, means for effecting movement of the carriage, a motor bracket pivotally secured to the carriage, a motor mounted on the bracket, a grinding wheel carried by the drive shaft of the motor and extending to a position adjacent the vise, means for adjusting the unpivoted end of the motor bracket to and from the carriage, and means for supplying cutting fluid to the grinding wheel.

2. Apparatus for grinding chip breaking shoulders and the like comprising a tool vise, a ball and socket support for the vise, means for clamping the vise in any desired tilted position, a base, means mounting the vise in a longitudinally adjustable position on the base, means for adjust-

ing the lateral position of the vise on the base, a carriage, means slidably mounting the carriage for movement parallel to the base but spaced laterally from the vise, means for effecting movement of the carriage, a motor bracket pivotally secured to the carriage, a motor mounted on the bracket, a grinding wheel carried by the drive shaft of the motor and extending to a position adjacent the vise, means for adjusting the unpivoted end of the motor bracket to and from the carriage, and means for supplying cutting fluid to the grinding wheel.

3. Apparatus for grinding chip breaking shoulders and the like comprising a tool vise, a ball and socket support for the vise, means for clamping the vise in any desired tilted position, a base, means mounting the vise in a longitudinally adjustable position on the base, means for adjusting the lateral position of the vise on the base, a carriage, means slidably mounting the carriage for movement parallel to the base but spaced laterally from the vise, means for effecting movement of the carriage, a motor bracket pivotally secured to the carriage, a motor mounted on the bracket, a grinding wheel carried by the drive shaft of the motor and extending to a position adjacent the vise, and means for adjusting the unpivoted end of the motor bracket to and from the carriage.

4. Apparatus for grinding chip breaking shoulders and the like comprising a tool vise, a ball and socket support for the vise, means for clamping the vise in any desired tilted position, a base, means mounting the vise on the base, means for adjusting the lateral position of the vise on the base, a carriage, means slidably mounting the carriage for movement parallel to the base but spaced laterally from the vise, means for effecting movement of the carriage, a motor bracket pivotally secured to the carriage, a motor mounted on the bracket, a grinding wheel carried by the drive shaft of the motor and extending to a position adjacent the vise, and means for adjusting the unpivoted end of the motor bracket to and from the carriage.

5. Apparatus for grinding chip breaking shoulders and the like comprising a tool vise, a ball and socket support for the vise, means for clamping the vise in any desired tilted position, a base, means mounting the vise on the base, means for adjusting the lateral position of the vise on the base, a carriage, means slidably mounting the carriage for movement parallel to the base, means for effecting movement of the carriage, a motor bracket pivotally secured to the carriage, a motor mounted on the bracket, a grinding wheel carried by the drive shaft of the motor and extending to a position adjacent the vise, and means for adjusting the unpivoted end of the motor bracket to and from the carriage.

6. Apparatus for grinding chip breaking shoulders and the like comprising a tool vise, a ball and socket support for the vise, means for clamping the vise in any desired tilted position, a base, means mounting the vise on the base, means for adjusting the lateral position of the vise on the base, a carriage, means slidably mounting the carriage for movement parallel to the base, means for effecting movement of the carriage, a motor, means adjustably mounting the motor on the carriage whereby the motor can be moved toward or from the carriage, and a grinding wheel carried by the motor and extending adjacent the vise.

7. In combination in apparatus for grinding

articles, means for clamping at any desired angle the article to be ground, a base, means for adjustably securing the clamping means to the base in a longitudinally and laterally adjustable position, a bar, means mounting the bar in a position extending longitudinally of the base and parallel thereto but spaced therefrom, said bar being laterally offset from the clamping means, a carriage, a plurality of longitudinally offset groups of rollers mounted on the carriage and engaging in rolling relation with the bar, a motor, means mounting the motor for movement to and from the carriage, means for adjusting the position of the motor with respect to the carriage, a grinding wheel driven by the motor, linkage means for moving the carriage along the bar, and means slidably supporting the carriage on the base at a point remote from the bar.

8. In combination in apparatus for grinding articles, means for clamping at any desired angle the article to be ground, a base, means for adjustably securing the clamping means to the base in a longitudinally and laterally adjustable position, a bar, means mounting the bar in a position extending longitudinally of the base and parallel thereto but spaced therefrom, said bar being laterally offset from the clamping means, a carriage, a plurality of longitudinally offset groups of rollers mounted on the carriage and engaging in rolling relation with the bar, a motor, means mounting the motor for movement to and from the carriage, means for adjusting the position of the motor with respect to the carriage, a grinding wheel driven by the motor, and linkage means for moving the carriage along the bar.

9. In combination in apparatus for grinding articles, means for clamping at any desired angle the article to be ground, a base, means for adjustably securing the clamping means to the base in a longitudinally and laterally adjustable position, a bar, means mounting the bar in a position extending longitudinally of the base and parallel thereto but spaced therefrom, said bar being laterally offset from the clamping means, a carriage, a plurality of longitudinally offset groups of rollers mounted on the carriage and engaging in rolling relation with the bar, a motor, means mounting the motor for movement to and from the carriage, means for adjusting the position of the motor with respect to the carriage, and a grinding wheel driven by the motor.

10. In combination in apparatus for grinding articles, means for clamping the article to be ground, a base, means for adjustably securing the clamping means to the base in a longitudinally and laterally adjustable position, a bar, means mounting the bar in a position extending longitudinally of the base and parallel thereto but spaced therefrom, said bar being laterally offset from the clamping means, a carriage, a plurality of longitudinally offset groups of rollers mounted on the carriage and engaging in rolling relation with the bar, a motor, means mounting the motor for movement to and from the carriage, and a grinding wheel driven by the motor.

11. In combination, a grinding wheel, means for driving the grinding wheel, means mounting the grinding wheel and driving means for sliding movement in a plane, a base, ball and socket vise means for supporting on the base an article to be ground, a screw extending radially of the ball and socket vise means, a handle nut associated

with the screw for clamping and unclamping upon a relatively short throw the ball and socket tilting of the vise means, a second screw substantially in alignment with the first screw, and a second handle nut associated with the second screw for clamping and unclamping upon a relatively short throw the vise means from the base.

12. In combination in apparatus for grinding articles, means for clamping the article to be ground, a base, means for adjustably securing the clamping means to the base in a longitudinally and laterally adjustable position, a bar, means fixedly mounting the bar in a position

5 extending longitudinally of the base and parallel thereto but spaced therefrom, said bar being laterally offset from the clamping means, a carriage, roller means on the underside of the carriage and engaging with the bar, a downwardly extending flange around substantially the entire outer periphery of the carriage and surrounding the bar and roller means and keeping them free of dust, a motor, means mounting the motor on the carriage for movement to and from the carriage, and a grinding wheel driven by the motor.

10 WALTER J. GREENLEAF.
